UNITED STATES PATENT OFFICE.

THOMAS W. MARCUM, OF CAIRO, INDIAN TERRITORY.

PLOW.

No. 823,799.

Specification of Letters Patent.

Patented June 19, 1906.

Application filed May 17, 1905. Serial No. 260,890.

To all whom it may concern:

Be it known that I, THOMAS W. MARCUM, a citizen of the United States, residing at Cairo, in the Choctaw Nation, Indian Territory, have invented certain new and useful Improvements in Plows, of which the following is a specification.

This invention relates to plows, and more especially to plow-points of that character which can be removed for resharpening or to be replaced by a new one with little trouble and loss of time and at less expense than where the point must be welded on by a blacksmith.

The object of my invention is to produce plows of the character outlined of simple, strong, durable, and inexpensive construction.

To this end the invention consists in certain novel and peculiar features of construction and organization, as hereinafter described and claimed, and in order that it may be fully understood reference is to be had to the accompanying drawings, in which—

Figure 1 is a perspective view of the landside of a plow embodying my improvement. Fig. 2 is a perspective view of the opposite side of the plow. Fig. 3 is a vertical section taken on the line III III of Fig. 2. Fig. 4 is a detail perspective view of the front end of the plow. Fig. 5 is a detail perspective view of the plow-point.

In the said drawings, 1 indicates the permanent point of the plow, the same being formed at its front end with the vertical shoulders 2 and the forwardly-projecting tongue 3, and at a suitable point rearward of the tongue the plow is provided with a hole 4. The removable point comprises the nose 5, beveled from opposite sides to a point, and the arm 6, projecting rearwardly from the landside of the point and adapted to lie snugly against the corresponding side of the permanent point 1, and said arm is provided with an aperture 7. The point 5 at the right-hand side of the arm is formed in its rear edge with a pocket 8. The removable point is slid rearwardly on the permanent point until the tongue of the latter engages the pocket of the former, the shoulders 2 bearing squarely against the rear edge of point 5 and the arm 6 fitting flatly against the landside of the point 1 and having its aperture 7 registering with hole 4. When the parts are thus arranged, a pin 9 is

fitted in said registering aperture and hole 55 and is riveted or upset at its ends so as to guard against any possibility of the removable point becoming disengaged from the permanent point. By this construction and arrangement it will be apparent that there is 60 but little strain on the pin or rivet, as its engagement with the rear portion of the arm 6 gives a long leverage to guard against any possibility of the arm swinging away from point 1, this leverage being supplemented by 65 the resistance to lateral movement offered by the projection of tongue 3 into pocket 8.

It will be apparent that there will be no tendency of the removable point shearing the rivet, because independent vertical movement of said removable point is prevented by its rear end bearing squarely against the vertical shoulders 2, which resistance toward vertical movement is likewise supplemented by tongue 3 fitting snugly in the pocket 8. 70 When it is desired to replace point 5 with a new one, one end of the rivet can be cut or filed off, and then said point 5 can be readily removed:

From the above description it will be apparent that I have produced a plow embodying the feature of advantage enumerated as desirable and that the same is susceptible of some modification as regards its form, proportion, detail construction, and arrangement without departing from the spirit of the invention.

Having thus described the invention, what I claim as new, and desire to secure by Letters Patent, is—

The combination with a plow provided at its front end with a tongue 3 and shoulders 2 above and below said tongue, and also with a hole 4, of a point having a nose 5 to fit squarely against shoulders 2 and pocket 8 to 95 receive tongue 3, and having also at one side of said pocket, an arm 6 adapted to fit against the landside of the plow and provided with a hole registering with the said hole of the plow, and a device extending through said registering holes and securing the point and the plow reliably together.

In testimony whereof I affix my signature in the presence of two witnesses.

THOMAS W. MARCUM.
